Attorney

UNITED STATES PATENT OFFICE.

HERBERT P. NORTON, OF PIERPONT, OHIO.

GENERATOR-COMMUTATOR CLEANER.

Application filed April 4, 1925. Serial No. 20,708.

To all whom it may concern:

Be it known that I, HERBERT P. NORTON, a citizen of the United States, residing at Pierpont, in the county of Ashtabula and State of Ohio, have invented certain new and useful Improvements in Generator-Commutator Cleaners, of which the following is a specification, reference being had to the accompanying drawings.

This invention relates to generator commutator cleaners and has for an important object thereof the provision of a device of this character primarily intended for use in cleaning the generator commutators of automobile ignition systems.

A further object of the invention is to provide a device of this character which is of small size and may be readily stored in a tool box and which includes means for storing a strip of sandpaper and guiding and holding the same while the device is being employed for cleaning the commutator.

A further object of the invention is to provide a device of this character which may be very cheaply and readily produced.

These and other objects I attain by the construction shown in the accompanying drawings, wherein for the purpose of illustration is shown a preferred embodiment of my invention and wherein:—

Figure 1 is a plan of a generator commutator cleaner constructed in accordance with my invention; and

Figure 2 is a longitudinal sectional view therethrough taken on the line 2—2 of Figure 1.

Referring now more particularly to the drawings, the numeral 10 indicates a frame formed centrally to provide an opening 11 therethrough. Through the side edges of the frame a bolt or other suitable pivot, as indicated at 12, is directed through this opening and provides a means for supporting a roll 13 of sandpaper. One end of the frame is formed to provide a handle 14 while the opposite end thereof has secured at opposite faces thereof a pair of outstanding guide strips 15 and 16.

The guide strip 16 has its free end turned inwardly, as at 17, and is provided at spaced points along its length with guide loops 18 through which the strip 13 from the roll

13 may be directed. The free end of the strip 16 is bent outwardly, as indicated at 19, and then down in closely spaced relation to the strip 16, as indicated at 20, just sufficient space being provided between the portion 20 and the strip 16 to admit of the end of the strip 13^a being slipped therebetween.

In the use of the device, the face of the strip 13^a lying between the ends of the guide strips 15, 16 is forced against the commutator face while the generator is in operation, cleaning the same in the usual manner. The strip being unbacked between the supports formed at 17 and 19 may conform to the shaping of commutators of different diameters. The frame 10 is preferably formed of insulating material. When the strip becomes worn, it is further withdrawn from the spool until a fresh surface is exposed between the supports 17, 19, and the end portion torn off so that just sufficient length is left to insert this end between the strip 16 and the reverted portion 20 thereof.

It will be obvious that the structure hereinbefore set forth is capable of a certain range change and modification without materially departing from the spirit of my invention and I accordingly do not limit myself to such specific structure except as hereinafter claimed.

I claim:

In a commutator cleaner, a frame formed at one end to provide a handle and having at its opposite sides thereof a pair of extended guide strips, the outer end of one of said guide strips being inbent, the outer end of the other guide strip being outwardly bent and reverted in closely spaced relation to the guide strip, the frame being formed intermediate the ends thereof with an opening housing a coil of stripped sandpaper, the end of the strip of sandpaper being passed about the ends of said supporting strips and engaged between said reverted portion and the strip to which it is attached, the first named supporting strip being provided at spaced points with guide loops through which the sandpaper strip is directed.

In testimony whereof I hereunto affix my signature.

HERBERT P. NORTON.
